United States Patent Office.

HENRY SHIREY, OF FOND DU LAC, WISCONSIN.

Letters Patent No. 74,856, dated February 25, 1868.

IMPROVEMENT IN DUMPING-WAGONS.

The Schedule referred to in these Letters Patent and making part of the same.

TO ALL WHOM IT MAY CONCERN:

Be it known that I, HENRY SHIREY, of the city of Fond du Lac, in the county of Fond du Lac, and in the State of Wisconsin, have invented certain new and useful "Improvements in Dumps for Vehicles;" and I do hereby declare that the following is a full, clear, and exact description thereof, reference being had to the accompanying drawings, and to the letters of reference marked thereon, in which—

Figure 1 is a side elevation.

Figure 2, an end view.

Figure 3, a section in perspective.

Figure 4, a section with the side of the bed of the vehicle removed.

The nature of my invention consists in the construction of a dumper-bed or body for wagons, as herein-after described.

To enable others skilled in the art to make and use my invention, I will describe its construction and operation.

In the construction of my invention I make the bed or body of the wagon of any convenient form, as seen in fig. 1. A, the bed or body of the wagon; b b b b, the bottom boards, with loops, e e e, attached to each board, for the purpose of drawing them out; d d d d are revolving supports, on which the bottom boards rest. These supports are composed of two parallel bars joined together with cross-bars d', the lower bar being the longer of the two, and is fixed in supports e e, which supports are firmly attached to the lower bed-rail in any suitable way. To the outer end of each of the revolving supports d, I attach a cam, f, which is connected to the sliding bar g, thus connecting each of the revolving supports to this sliding bar. At the rear end of bar g is attached a lever, h, with its fulcrum, k, (which is a headed bolt,) attached to the front end of the bed-rail, and said lever extends up nearly the height of the bed or body of the wagon; and when the braces are turned into position to support the bottom, this lever is held in position by a revolving brace, i, attached to the side of the bed, (as seen in fig. 1,) and which holds the gate B shut. Cross-bars j j are placed across the bottom, attached to the under side of the bottom rails of the bed, to prevent the bed from spreading apart.

In the operation of my invention, when I wish to load the vehicle, the boards b of the bottom having been placed in proper position, the lever h having been pushed backward, the supports d are turned down on their sides, so as to easily adjust the boards b. When thus adjusted, the lever h is drawn up, pushing back the bar g, carrying the revolving supports d up to a vertical position, and pressing them against a cleat on the front end, and the gate B at the rear end. The upper bars of supports d being pressed tightly up against the boards b, hold them in place, at the same time supporting them so that the cross-bars that are commonly framed in the bed are dispensed with. Thus prepared, the bed may be filled or loaded, and the vehicle removed to any required place with its load in perfect safety. When it is required to dump the load, it is only necessary to detach the lever h from the brace i, and by its own weight the load presses down the supports d, and relieves the boards of the pressure of the supports. The boards b are then caught by the loops e, and are readily drawn out, thus directly dumping the load. It requires comparatively but a small amount of force to draw out one of the boards b at a time; and after the first board has been drawn, each succeeding board is drawn out with less resistance, as part of the load fall through the first opening, greatly relieving the pressure on each succeeding board, and thus the operation is completed.

Having thus fully described my invention, what I claim as new, and desire to secure by Letters Patent, is—

1. The revolving supports d d d d, cams f, bar g, lever h, fulcrum k, and brace i, constructed substantially as described and operating as set forth.

2. The bottom boards b b, loops e e, in combination with a body or wagon-bed, when constructed and operating substantially in the manner and for the purposes set forth.

In testimony that I claim the above-described certain new and useful "improvements in dumps for vehicles," I have hereunto signed my name, this twentieth day of August, 1867.

HENRY SHIREY.
